FIG. 1 is a perspective view for a squeegee for flat and curved windows showing my new design;

FIG. 2 is a front elevation view thereof;

FIG. 3 is a top plan view thereof;

FIG. 4 is an elevational view taken from the left side thereof;

FIG. 5 is an elevational view taken from the right side thereof;

FIG. 6 is a back plan view thereof; and,

FIG. 7 is a bottom plan view thereof.

The broken lines in FIG. 6 depict portions of the squeegee for flat and curved windows that form no part of the claimed design.
